CUTTER

Charles Clair Patton, Port Caledonia, Cape Breton
Island, Nova Scotia, Canada

Application August 13, 1948, Serial No. 44,163
In Canada September 8, 1947

3 Claims. (Cl. 164—41)

This invention relates to cutters for sheet material and the like and more particularly to cutters which are particularly adapted for hand operation in small work shops and on the job.

Cutters of this kind, in which a shearing blade is pivoted between two bolster plates and operates to shear out a section of the material being cut are already known and previously known cutters of this type operate satisfactorily for the cutting of fairly thin sheets of fairly pliable material such as roofing tin. Where fairly thick, rigid material such as, for instance, $\frac{1}{8}$ and $\frac{1}{4}$ inch steel plate has had to be cut, however, two difficulties have arisen which have until the present time prevented the use of this convenient type of cutter.

In the first place, the friction between the blade and the material being cut becomes so great that it is very difficult, if not impossible, to advance a sheet through the cutter between successive strokes of the blade and the sheet material has had to be dislodged from the blade after each cut by a hammer stroke or some other violent means.

In the second place, such a large mechanical advantage is necessary when cutting such thick material that the cut must be commenced at a point on the blade fairly close to the point at which the blade is pivoted. This results in there being a fairly large angle between the blade and the sheet material which causes the sheet material to slip backwards when force is applied to the cutting blade. It has been found to be extremely difficult to initiate a cut in fairly thick sheet steel using previously known cutters of this type.

The above mentioned difficulties have compelled the employment either of power shears or acetylene torches for the cutting of the type of material mentioned. Both of these methods are cumbersome, and excessively costly for small work shops and on the job. There is, moreover, the added disadvantage that it is not easy to cut to exact dimensions with an acetylene torch, and in the case of power shears, the edge of the cut metal is almost invariably deformed, making extra work necessary before the cut material can be used for the purpose intended.

Accordingly it is the object of the present invention to provide a cutter of the type described which is particularly adapted for hand operation in small work shops and capable of cutting fairly thick, rigid material such as, for instance, $\frac{1}{8}$ and $\frac{1}{4}$ inch steel plate.

It is another object of the invention to pro-

vide such a cutter which includes means for freeing the material being cut from the binding action of the blade upon the raising thereof after each successive cut.

It is a further object of the invention to provide such a cutter which is designed to minimize the tendency of the material being cut to slide out from under the blade when cutting force is applied.

It is a still further object of the invention to provide such a cutter in which means are provided for eliminating binding between the sheared out portion of the work piece and the edges of the bolster plates so that the work piece may freely be advanced after each cut.

Various other objects and advantages of my invention will appear in the following detailed specification.

A cutter according to my invention has the following main features:

(a) An irregular cutting edge comprising a series of corrugations or teeth to grip in a positive manner the material being cut.

(b) A transversely extending portion of reduced thickness extending completely across the blade and positioned to extend upwardly from the cutting plane a distance at least equal to the maximum thickness of the work to be cut when the blade is in a raised position, said portion of reduced thickness extending at least into the cutting plane when the blade is in said raised position.

(c) Stripping means in association with the thin portion for freeing the material being cut from the binding action of the blade upon the raising thereof and shifting said material to a position astride the thin portion of the blade so that it may be freely advanced into position for a subsequent cut. Such stripping means preferably comprise selectively positionable stripping pins adapted to be selectively positioned in a series of holes bored through the blade for that purpose adjacent to the outer side of the thin portion of the blade, that is, on the side thereof remote from the pivot point of the blade. Thickened portions of the blade itself would fulfil the purpose, but a more versatile cutter is obtained by the provision of selectively positionable pins.

In addition to the above main features, the following subsidiary features taken singly or in combination are particularly desirable:

(1) A blade which, apart from the thin portion gradually increases in thickness from the pivoted end outwards, and increases in thickness

from the cutting edge across the blade with the tapers meeting along a line running obliquely from the back of the blade to a point at or beyond the outer end of the cutting edge. A blade of this tapering nature materially reduces the friction which must be overcome by the stripping pins.

(2) A cutting edge of which the advanced end inclines upwardly slightly towards the pivot of the blade at a small angle to the main portion of the edge, thus decreasing the angle at which the cutting edge initially meets a piece of material being cut. This feature minimizes the tendency of the material to slide out from under the blade when force is applied.

(3) The bolster plates are of undercut design and on the blade is a slightly thickened portion at a point on the lower edge thereof and just to the pivot side of the thin portion of the blade. Such thickened portion is adapted, during a cut, to ride within the space defined by the undercut portions of the bolster plates, and during advancement of the work piece when the blade is in a raised position, wedges between the bolster plates thus pressing them apart, minimizing any tendency for the sheared out portion of the work piece to bind between the bolster plates.

One embodiment of the invention is illustrated in the accompanying drawings, in which

Figure 1 is a perspective view of a hand-operable cutter according to the invention.

Figure 2 is a fragmentary side elevation of the cutting edge of the blade.

Figure 3 is a bottom elevation of the fragment of the blade shown in Figure 2.

Figure 4 is an enlarged sectional view taken along the section A—A of Figure 2; and

Figure 5 is a fragmentary sectional view taken through the bolster plates along the section B—B of Figure 1 showing the undercut portions thereof.

Referring now more specifically to the drawings, a cutter according to the invention comprises two bolster plates 10 and 11 which are suitably connected to base plates 12 and 13 which are secured to a base 14.

The bolster plates 10 and 11 are suitably bored to accommodate the pivot pin 15 which pivots the blade 16 about a suitable pivot hole 17 formed therein.

A suitable handle member H is secured to the outer end of the blade 16 by bolts 18.

The sides of the blade 16 are formed with two tapers. One taper runs longitudinally, and the blade increases in thickness towards the handle end. A second taper runs in a transverse direction starting from the cutting edge 19 of the blade, which is parallel sided, and the blade increases in thickness in a transverse direction. The two tapers meet along a line 20 which runs obliquely across the blade, and is interrupted by a thin substantially parallel sided portion 21 of the blade.

The thin portion 21 runs from an advance portion of the cutting edge 19 across the blade. The thin portion 21 is of reduced thickness, being slightly thinner than the rest of the cutting edge 19 by an amount sufficient to enable the said thin portion to pass freely through a cut made by the blade when the blade has been raised and the work is advanced following a cutting stroke. A thin portion 21 which is approximately $\frac{1}{64}$ of an inch thinner than the remainder of the cutting edge 19 has been found to be suitable.

Two holes 22 and 23 are provided in the blade adjacent the thin portion 21 on the side thereof remote from the pivot hole 17, and a stripping pin 24 is adapted to be selectively fitted in either one of the holes 22 and 23.

The cutting edge 19 is formed with a series of corrugations such as teeth 25, and an advanced portion thereof 26, which suitably extends across the end of the thin portion 21, is inclined slightly upwardly toward the pivot hole 17 to reduce the angle at which the cutting edge will initially engage a piece of material being cut.

Adjacent the inner end of the cutting edge 21 is a thickened portion 27 of the blade, which is adapted to operate in connection with the bolster plates 10 and 11 as will be described later.

The bolster plates 10 and 11 are of heavy substantially L-shaped cross section, and are bevelled at a suitable angle over their working portions 28 and 29 respectively. The bolster plates 10 and 11 are undercut throughout their length by cuts 30 and 31 respectively, to produce clearance for the waste cuttings and a space in which the thickened portion 27 will bear against the bolster plates at a point which is preferably suitably bevelled as shown in dotted lines in Figure 5, and a slight spreading of the bolster plates will occur. This spreading of the bolster plates provides clearance for the waste cuttings which are thereby permitted to drop into the cavity formed by the undercut portions 30 and 31.

The operation of the blade 16 varies slightly depending upon the thickness of the material being cut.

When cutting fairly thin sheet metal up to approximately $\frac{1}{16}$ inch in thickness, the stripping pin is placed in the upper hole 22. With the blade 16 in the fully raised position the material to be cut is placed on the bolster plates, and a cut is commenced. As the cut proceeds, the material rides up the taper and the edges of the cut are slightly spread apart. On completion of the cut the blade 16 is raised to a substantially vertical position. The material being cut is held down by the operator and works around the pin 24 as the blade is raised until the blade reaches the vertical position at which point the cut is astride the thin portion 21 of the blade and may freely be advanced therealong and along the bolsters for a second cut.

Where thicker metal is to be cut, the stripping pin 24 is placed in the lower position in hole 23, and the pin 24 also acts as a stop during the cut, so that only the advance portion of the cutting edge 19 where the mechanical advantage is greatest is used in making the cut.

During subsequent cuts it is no longer necessary for the operator to hold down the material during the raising of the blade, because the effect of the taper of the blade upon the raising thereof is to further spread the cut at a point intermediate along its length by forcing the taper at the back of the blade in a downward direction, thus urging the material down on the bolster plates at that point as the blade is raised.

What I claim is:

1. A cutter of the type having a blade pivoted adjacent one end thereof between two bolster plates defining a cutting plane, said blade having a transversely extending portion of reduced thickness extending completely thereacross and positioned to extend upwardly from said cutting plane a distance at least equal to the maximum thickness of the work to be cut when the blade is in a raised position, said portion of reduced thickness extending at least into said cutting

plane when the blade is in said raised position, and stripping means projecting from at least one side of said blade immediately adjacent the side of said portion remote from the pivoted end of the blade for engaging the upper side of the workpiece as the blade is raised following the cutting stroke to cause the workpiece to pivot therearound so that the cutting edges of the material of the workpiece lie astride said portion of reduced thickness.

2. A cutter as defined in claim 1 in which the blade is formed with a hole adjacent the side of said portion of reduced thickness remote from the pivoted end of the blade and in which said stripping means comprises a stripping pin designed to fit and be retained within said hole.

3. A cutter as defined in claim 1 in which said bolster plates are formed with longitudinally undercut portions immediately beneath said cutting plane and in which boss means are provided adjacent the lower edge of the blade on the side

of said portion of reduced thickness nearest the pivoted end of the blade, said boss means being positioned to ride within the space defined by the undercut portions of the bolster plates while a cut is being made and to wedge between the bolster plates as the blade is raised to said raised position following a cut to force the bolster plates apart as said raised position is reached.
